Primary Examiner — Susan Moon Lee(74) *Attorney, Agent, or Firm* — Weiss & Moy, P.C.; Jeffrey D. Moy(57) **CLAIM**

The ornamental design for a sliding door, as shown and described.

DESCRIPTION

FIG. 1 is a front view of a sliding door;

FIG. 2 is a rear view thereof;

FIG. 3 is a side view thereof;

FIG. 4 is an opposite side view thereof;

FIG. 5 is a top view thereof; and,

FIG. 6 is a bottom view thereof.

The nature of the front and rear surfaces of the sliding door are that of a flat plane.

The broken line depictions form no part of the claimed design.

1 Claim, 4 Drawing Sheets(56)
